UNITED STATES PATENT OFFICE.

MOSES S. OKUN, OF NEW YORK, N. Y.

ROTARY ENGINE AND MOTOR.

No. 813,018.

Specification of Letters Patent.

Patented Feb. 20, 1906.

Application filed April 25, 1902. Serial No. 104,636.

To all whom it may concern:

Be it known that I, MOSES S. OKUN, a citizen of the United States, residing in the borough of Manhattan, New York city, county and State of New York, have invented certain new and useful Improvements in Rotary Engines and Motors, of which the following is such a full, clear, and exact description as will enable any one skilled in the art to which it appertains to make and use the same, reference being had to the accompanying drawings, forming part of this specification.

In many known forms of rotary engines and motors a serious defect results from the fact that the rotary piston is fixed upon the shaft so that it cannot yield laterally in order to compensate for the lateral displacement or the tipping of the shaft out of alinement as the bearing becomes worn, and one of the consequent evils of this is the undue wearing of the sides of the casing or cylinder by the tipping of the piston.

One of the principal objects of my present invention is to prevent the lateral displacement of the shaft or its tipping out of its true axial line from tipping or displacing the connected piston, and this I accomplish by providing a relative lateral yielding movement between these two parts.

The invention further seeks to provide a simple, cheap, and efficient form of engine or motor of a comparatively light weight and in which the drawing in of the explosive mixture, the compression thereof, the ignition and expansion, and final exhaust of the gases is all accomplished in one revolution of the piston.

To these ends my invention consists in the various novel and peculiar arrangements and combinations of the several parts of the apparatus, all as hereinafter fully set forth and then pointed out in the claims.

I have illustrated types of my invention in the accompanying drawings, wherein—

Figure 1 is an end view of my improved apparatus. Fig. 2 is a view of the apparatus shown in Fig. 1 in section on a central vertical plane transverse to the shaft. Fig. 3 is a similar sectional view to Fig. 2 of a modified form of the apparatus. Fig. 4 is a sectional view of the apparatus shown in Fig. 3, the plane of the section being vertical and central of the apparatus.

Referring to the drawings, in which like numbers of reference designate like parts throughout, 2 is a casing or so-called "cylinder"

comprising a peripheral part 3 and two flat sides 4 4, fitted to each other and suitably secured together to form a fluid-tight chamber. A shaft 5 is mounted in suitable bearings in the sides of the casing and extends through the casing, and upon it is mounted a body or piston 6, which in this form is cylindrical in shape and of a diameter slightly less than the smaller diameter of the oval-shaped chamber 2, as is clearly indicated in Fig. 2.

The circular or cylindrical piston 6 is provided upon its periphery with a number of spring-pressed vanes or partitions 7, which are shown as six in number and are arranged about the same distance apart. These vanes each work in a recess 8 in the piston, in which is arranged a spring 9, which always acts to force the vane 7 from the recess and project it from the piston and cause it to bear or seat itself against the interior surface of the peripheral part 3 of the cylinder. The piston-body 6 is mounted nearer to one end of the oval-shaped casing 2 than the other, so that the crescent-shaped space 10 at one end of the cylinder is smaller than the other space 11 at the other end, as indicated in Fig. 2. The piston 6 is fitted nicely between the sides 4 4 of the cylinder or casing, and each of the vanes 7 fit between these two sides in a similar manner, so that the space between any two adjacent vanes or plates may serve as either a compression or an expansion chamber as the piston is rotated in the direction indicated by the arrow *a* in Fig. 2.

Instead of mounting the piston-body 6 fast upon the shaft 5 in the usual manner I introduce between these two parts a yielding joint, which in the present instance comprises an outer yoke 12, having two opposite projections or lugs 13, which fit loosely in sockets 14, formed in the wall of the central opening 15 of the piston-body, so that the latter may have a slight play on the central line or axis of the lugs 13. Within the outer

yoke 12 is arranged a similar yoke 16 of smaller size and with opposite projections or lugs 17 extending therefrom at right angles to the lugs of the outer yoke and fitting loosely in sockets 18, formed in the wall of the central opening 19 of the outer yoke, so that the outer yoke may rock on the lugs 17 as a center. This inner yoke 16 is made fast to the shaft 5, and the rotation of this shaft serves to drive the piston-body 6. By virtue of this yielding joint between the piston and its shaft the piston always tends to maintain

its true position in a plane parallel with the sides of the casing even though one end of the shaft 5 should be tilted or displaced from its true axial position by reason of its bearings becoming worn or for any other reason. This prevents the piston-body 6 from bearing or pressing upon any particular part of the sides of the casing in which it turns with too great a pressure, which defects usually occur where the piston is rigid with the shaft, and such undue pressure at particular points results in cutting into the metal of the walls of the casing and injuring the apparatus, and, what is more serious, it largely increases the friction and produces leaks.

Referring again to Figs. 1 and 2, which show a construction that may be used as a gas-engine, the mixture of air and gas is introduced through an inlet-pipe 20, having a branch pipe 21, which leads to a point upon the interior of the casing slightly distant from the point where the pipe 20 enters, this arrangement being adopted merely to enable the mixture to be more freely introduced into the interior of the casing. The air and the usual regulated quantity of gas which is mixed therewith is introduced to the inlet-pipes 20 and 21, and by the rotation of the piston 6 with its series of vanes 7 it is drawn into the space between two adjacent vanes or partitions as such space is presented to the inlet. After the second vane 7 of a pair has passed the inlet-pipe with its charge of the explosive mixture between such vanes the continued movement of the piston serves to carry the two vanes or plates around, the leading vane being gradually forced into its recess, while the following vane is gradually projected, and then the following vane is forced inwardly, and the space between the two vanes containing the charge is gradually reduced in size, thereby compressing the mixture to a degree that renders it ready for explosion, and when this compression has been effected the piston has moved the vanes around to a point about opposite the inlet-point, where the compressed charge is then presented to an igniting device, which consists in a small chamber 22, formed in the wall of the periphery of the casing and into which extend two electrodes 23 and 24, which are connected, respectively, with an electric circuit, (indicated by the wires 25 and 26.) The electric spark or arc between the electrodes 23 and 24 serves to ignite the compressed charge of air and gas and explode it. The igniting device may contain an incandescent body or any suitable well-known form of igniting means. When the explosion of the mixture occurs, the leading vane of the pair between which the exploding charge is carried has passed over the igniting device, so that it begins to be projected, and thereby gradually increases the surface of the vane or plate 7, against which the force of expansion

of the exploded gases may act, with the result that practically the entire force of the explosion is directed against the leading vane as it moves onward, and in this way the piston is caused to rotate. The continued movement of the pair of vanes containing the exploded charge carries the same around to the exhaust-pipes 27 and 28, by means of which the exploded gases which have been used to rotate the piston are discharged from the apparatus.

In Figs. 3 and 4 I show a construction of a gas-engine in which the vanes or plates 7 are located within the walls of the periphery of the casing 2, and the explosive mixture of air and gas is introduced through a pipe 20 to a circular duct or groove 29 in the side of the piston-body 6 and passes thence through a port 30 from the periphery of the piston into the space between two of the vanes or plates 7, which space gradually decreases in size by the rotation of the piston, whereby the explosive charge is compressed, and at the time such compression is reached the igniting device 22, 23, and 24, which is mounted on the periphery of the piston, is in such relative position as to ignite the charge and explode it. The force of the exploded charge is directed against the periphery of the piston-body 6, which in this case is of an oval form, while the interior of the casing 2 is cylindrical. This difference in shape of the moving and the fixed part causes the force of the explosion to be transmitted to the so-called "high part" of the oval-shaped piston, and thereby rotates it. The exhaust in this form of the apparatus comprises a circular duct or groove 31, upon the opposite side of the piston from the inlet 29, and a port 32, which opens upon the periphery of the piston, as indicated in dotted lines in Fig. 3. This exhaust-duct 31 is in constant communication with the exhaust-pipe 33, located in the side of the cylinder 2. In this form of the apparatus the electric wires 25 and 26 are connected with contacts which bear upon two contact-rings 34 on the rotating shaft 5, and from these rings 34 wires are led through the interior 35 of the shaft, which is made hollow for this purpose. From the shaft these wires pass to the electrodes 23 and 24, as indicated by dotted lines in Fig. 3.

As is well known, the exploded charge of the compressed mixture in a gas-engine is of a high temperature and of a very high pressure. In order to provide a comparatively large surface against which the explosive force of the charge may act in driving the piston, as well as to increase the size of the exhaust-chamber of the gases, I make the crescent-shaped chamber 11 of a considerably larger area than the corresponding chamber 10, into which the mixture is introduced and subsequently compressed.

It will be noted that in the use of my in-

vention as a gas-engine the drawing in of the explosive mixture of air and gas, the compression of the same, its explosion and expansion, and the exhaust thereof are all accomplished in one revolution of the piston, and so far as I am aware this is a novel feature in this type of apparatus.

The modification of the apparatus shown in Figs. 3 and 4 is provided with the yielding joint between the shaft and the piston, the same as described in reference to the primary form in other figures.

From the foregoing it will be readily understood that the sides of the piston are constantly maintained in true contact with the sides of the casing against which they snugly fit, and I thus avoid the excessive friction and cutting of such parts as occurs where the piston and shaft are rigid with each other.

20 I wish to be understood as not limiting my invention to the precise forms of construction herein set forth, as various modifications may be made in the different parts thereof without, however, departing from the spirit of my 25 invention.

While I have illustrated my invention in the form of a gas or explosive engine, it will of course be understood that the invention is equally applicable to a steam or other engine, 30 as well as to motors, pumps, and the like; and I have considered it unnecessary to illustrate any other form than that herein set forth.

Having thus described my invention, what I claim, and desire to secure by Letters Patent, is—

1. A rotary engine, motor or the like, comprising the combination of a casing and a piston or movable element therein, which snugly fits the sides of the casing, a shaft connected 40 with said movable element or piston, and means for permitting a relative lateral movement between the shaft and the movable element or piston, substantially as and for the purpose set forth.

2. A rotary engine, motor or the like, comprising the combination of a casing and a piston or movable element therein, which snugly fits the sides of the casing, a shaft connected with said movable element or piston, and 50 means for permitting a relative lateral angular movement between the shaft and the movable element or piston, substantially as and for the purpose set forth.

3. A rotary engine, motor or the like, comprising the combination of a casing and a movable element or piston, which snugly fits the sides of the casing, a shaft connected with said movable element or piston by the means of a laterally-yielding joint consisting 60 of a projection or projections carried by one part and a bearing or bearings or cavities for the projections carried by the other part, substantially as and for the purpose set forth.

4. A rotary explosive - engine comprising 65 the combination of two elements having rela-

tive rotary movement and having different forms so as to provide a suitable working space between said elements, and the said elements fitting snugly to each other at certain points to prevent the leakage of fluid, a 70 set of partitions adapted to be projected and retracted during the relative rotary movement and dividing the said working space into separate sections, which sections constitute, respectively, chambers wherein the explosive mixture is introduced and in succession compressed, ignited and expanded and finally exhausted therefrom, said cycle of actions being completed at every revolution in each section, substantially as and for the purpose set forth.

5. A rotary explosive - engine comprising the combination of two elements, of which one fits snugly to the sides of the other and having a relative rotary movement, one of 85 said elements being of an oval form for providing between the two a compression, explosion and expansion chamber, and means operated and controlled by each complete revolution of the movable element for successively drawing into the said chamber the explosive mixture, compressing the same, igniting, exploding and exhausting it, substantially as and for the purpose set forth.

6. A rotary explosive - engine comprising 95 the combination of two elements having relative rotary movement, a suitable working space being provided between said elements and the said elements fitting snugly to each other at certain points to prevent the leakage of fluid, a set of partitions adapted to be projected and retracted during the relative rotary movement and dividing the said working space into separate sections, which sections constitute, respectively, chambers 100 wherein the explosive mixture is introduced and in succession compressed, ignited, and expanded and finally exhausted therefrom, such successive actions taking place in each of the said sections during one revolution, 110 each section of such space formed between two adjacent partitions being twice reduced and enlarged in its volume during each revolution of the said movable element, said cycle of actions being completed at every revolution 115 in each section substantially as and for the purpose set forth.

7. A rotary explosive - engine comprising the combination of a casing and a movable element or piston which fits snugly to the 120 sides of the casing, one of said elements being of an oval form for providing between the two a space divided into compartments, each of which is twice alternately reduced and increased in its capacity or area during one revolution of the piston, and means operated and controlled by each complete revolution of the movable element for successively drawing into the said chamber the explosive mixture, compressing the same, igniting, exploding 130

ing and exhausting it, substantially as and for the purpose set forth.

8. The combination of a casing and a body or piston mounted therein and provided with a shaft, the said body or piston and casing having a relative rotary movement and each fitting against the sides of the other, a yoke fixed upon the shaft and provided with opposite projections forming bearings for a main yoke, a main yoke mounted upon said fixed yoke and provided with opposite projections constituting bearings for the piston, said piston being mounted upon said main yoke, whereby the piston and its shaft have a lateral yielding movement relative to each other, substantially as and for the purpose set forth.

9. The combination of a casing, a piston mounted within said casing and having a relative rotary movement, the periphery of the piston and the interior of the casing being so related as to provide two crescent-shaped spaces at diametrically opposite points and such spaces serving as the compression and expansion chambers respectively a series of movable vanes normally closing across each of said spaces, an inlet-pipe for supplying the explosive mixture to the compression-chamber and an exhaust-pipe connected with the expansion-chamber, and an igniting device for exploding the mixture when the same is compressed, substantially as and for the purpose set forth.

10. The combination of a casing, a piston mounted within said casing and having a relative rotary movement, the periphery of the piston and the interior of the casing being so related as to provide two crescent-shaped spaces 10 and 11, respectively, at diametrically opposite points and such spaces serving as the compression and expansion chambers respectively, a series of movable vanes 7 normally closing across each of said spaces, an inlet-pipe for supplying the explosive mixture to the compression-chamber and an exhaust-pipe connected with the expansion-chamber, and an igniting device for exploding the mixture when the same is compressed, substantially as and for the purpose set forth.

11. The combination of a casing and a body or piston mounted therein and provided with a shaft, the said body or piston and casing having a relative rotary movement and each fitting snugly against the sides of the other, and the said body or piston and its shaft having a universal joint between them to permit relative lateral yielding and at the same time cause them to rotate in response to each other, substantially as and for the purpose set forth.

12. A rotary engine, pump or the like, comprising the combination of a casing and a movable element fitting snugly therein to the sides of the casing, a shaft connected with said movable element and actuated thereby,

said shaft and movable element having a relative oscillatory or pivotal motion, substantially as and for the purpose set forth.

13. A rotary engine, pump or the like, comprising the combination of a stationary and a movable element fitting snugly to each other, a space between the two said elements and into which the gas or fluid is introduced, the two said elements fitting snugly against each other in order to prevent the escape of the said gas or fluid from the said space, a shaft on which the movable element is mounted, and said shaft and movable element having a relative lateral motion, substantially as and for the purpose set forth.

14. A rotary engine, pump or the like, comprising the combination of a stationary and a movable element fitting snugly to each other, a space between the two said elements and into which the gas or fluid is introduced, the two said elements fitting snugly against each other in order to prevent the escape of the said gas or fluid from the said space, a shaft on which the movable element is mounted, and said shaft and movable element having a relative oscillatory or pivotal motion, substantially as and for the purpose set forth.

15. A rotary engine, pump or the like, comprising the combination of a stationary and a movable element fitting snugly to each other, a space between the two said elements and into which the gas or fluid is introduced, the two said elements fitting snugly against each other in order to prevent the escape of the said gas or fluid from the said space, a shaft on which said movable element is mounted and a universal joint between said shaft and movable element, substantially as and for the purpose set forth.

16. A rotary engine, pump or the like, comprising the combination of a stationary and a movable element fitting snugly to each other, a space between the two said elements and into which the gas or fluid is introduced, the two said elements fitting snugly against each other in order to prevent the escape of the said gas or fluid from the said space, a shaft on which said movable element is mounted, the joint between said shaft and movable element comprising one or more projections carried by one part and fitting in bearings or cavities carried by the other part, substantially as and for the purpose set forth.

17. A rotary explosive or like engine comprising the combination of a suitable casing and a rotary piston mounted therein and fitting snugly to the sides of the casing, a suitable space between the piston and casing varying in its distance between the two so as to make such space of a gradually-increasing size from one point to another, the said space being contracted at two places and enlarged at two places intermediate between the contracted ones, a set of partitions dividing said space into separate sections and said parti-

tions being projected and retracted as the piston rotates, an inlet-pipe for supplying the explosive mixture to the interior of the casing and an exhaust - pipe leading from said 5 casing, and an igniting device, the said explosive mixture being introduced into each of said sections once during each complete revolution of the piston and being compressed, ignited and expanded in and exhausted from each of said sections once during each revolution, substantially as and for the purpose set forth.

18. A rotary explosive-engine comprising the combination of two elements having relative rotary movement, a suitable working space being provided between said elements and the said elements fitting snugly to each other at certain points to prevent the leakage of fluids, a set of partitions adapted to be projected and retracted during the relative ro-

25 tary movement and dividing the said working space into separate sections, which sections constitute, respectively, chambers wherein the explosive mixture is introduced and in succession compressed, ignited and expanded and finally exhausted therefrom, said cycle of actions being completed at every revolution in each section, and means for effecting said ignition comprising an igniting-chamber in direct and constant communication with said working space between the two said elements, substantially as and for the purpose set forth.

30 In testimony whereof I have hereunto set my hand in the presence of the two subscribing witnesses.
